UNITED STATES PATENT OFFICE.

ROBERT SCHLEICHER, OF LOUISVILLE, KENTUCKY.

MACHINE FOR MANUFACTURING BOXES.

SPECIFICATION forming part of Letters Patent No. 515,026, dated February 20, 1894.

Application filed October 30, 1893. Serial No. 489,489. (No model.)

To all whom it may concern:

Be it known that I, ROBERT SCHLEICHER, a citizen of the United States, residing at Louisville, in the county of Jefferson and State of Kentucky, have invented certain new and useful Improvements in Machines for Manufacturing Boxes, of which the following is a specification.

My invention relates to machines for manufacturing or assembling boxes, and consists in various features hereinafter set forth and claimed.

In the drawings,—Figure 1 is a perspective view of my improved machine with all the parts, the box-head support in working position, the said box-head support being raised up in order to show its support; Fig. 2, a side view; Fig. 3, a top plan view; Figs. 4 and 5, views illustrating the construction of the box-head support; Figs. 6 and 7, end and face views respectively, of the fixed jaws; and Figs. 8 and 9, similar views of the movable jaws.

A indicates the bed or frame of the machine which, in its preferred construction, comprises a single casting having four equally spaced radial arms A', each of which is provided with a longitudinal L-slot A².

At the center of the bed or frame, on the under side, is a hub A³, Figs. 1 and 2, through which extends the shaft or rod B carrying at its upper end the box-head support or supporting plate C,—Figs. 1, 3, 4 and 5,—the said plate C lying normally upon the upper face of the frame or bed A, and held in such position by means of a set screw a passing through the hub and bearing upon the rod B. In Fig. 1 of the drawings, this plate or support C is shown as raised or elevated, in order to more clearly illustrate its form; but it is to be remembered that this is not the position it occupies in use excepting for shallow boxes. Plate or support C is of course of a form and size of the box to be made, and is provided with a raised central or body portion b and lateral flanges c, as shown in Figs. 1, 3, 4 and 5; the said body portion fitting within the sides or walls and serving to support the box-head, which lies flatly thereon, while the flanges or rim support the upright sides of the box at their lower edges.

The present machine is designed more par-

ticularly for the manufacture of that class of boxes in which the head is seated at its edges in grooves in the inner faces of the sides; and as this groove is at a distance from the lower edges of the sides, it is necessary to hold the head at a distance above the lower edges of the sides. For this reason the plate C is provided with a raised body portion b, which is shown in Fig. 5 as supporting the head x in proper position to enter the grooves in the sides y.

The plate or support C will advisably be provided with holes or openings which permit the dirt, &c., to fall therethrough and to avoid the plate adhering to the box-head.

Mounted upon the upper faces of two of the arms A' of the bed or frame, are the fixed jaws D and D', which are held in any desired position upon the said arms by means of bolts d which carry at their lower ends a plate e, Figs. 6 and 7, which fits the slot in the arms. If one bolt d were used, the said bolt would have merely a head to fit and engage the wider part of the slot, but where two bolts d are used,—and two will be found preferable, as they prevent any lateral play,—it will be found better to connect them by a plate e, as shown. These jaws D D' are similar to each other, that is, they each comprise an upright body portion f, horizontal ways g projecting laterally therefrom, and bearing bars h adjustable longitudinally upon the ways and designed to be clamped in their adjusted positions by screws i. It will be observed, however, that the ways or arms g of the jaw D' are shorter than those of the jaw D, and that the said arms or ways g of the jaw D' extend inward between those of the jaw D.

The jaws D and D' may be independently adjusted upon their respective arms or supports A'.

The movable jaws E and E' are similar to each other and to the fixed jaws, each comprising an upright body portion f, horizontal arms or ways g, and bearing bars h and their fastening bolts or screws i. The jaw E, like the jaw D, has longer arms g than has the jaw E', the short arms g of the latter, as well as of jaw D', extending between the arms of the jaws E, see Figs. 2 and 3.

The jaws E E' are provided each with a flanged longitudinal rib j on the under side,—

Figs. 8 and 9,—which enters the groove A' and causes the said jaws to always move in right lines toward and from the fixed jaws D and D'.

- 5 In order to actuate or move the jaws E E', I employ two levers F F, one for each jaw. These levers are pivoted to swing horizontally upon the standards or supports G, which, as shown in Figs. 1, 2 and 3, are bolted or otherwise rigidly affixed in position upon the bed or frame. In each of the movable jaws, I form a slot k, into which the inner end of the lever projects, the said inner end of the lever being provided with a cam slot l, to receive a pin or stud m carried by the said movable jaw. By swinging the levers laterally, the jaws may be made to move inward or outward as desired.
- In making a box with this machine, the head of the box is placed upon the plate or support C, and the sides or side pieces are set up vertically upon the flanges or rim of said support, see Fig. 5. The levers F are now swung laterally and the jaws E E' moved inward toward the jaws D D',—this inward movement 25 of the jaws causing the tenons and mortises at the edges or corners of the box sides to firmly interlock, and this too without first giving them a start, as has heretofore been customary. Not only are the sides or side pieces which 30 are supported by the movable jaws, caused to interlock with those supported by the fixed jaws, but the edges of those supported by the fixed jaws are caused to interlock and the edges of those supported by the movable jaws 35 are also caused to interlock by this inward movement of the jaws E E'. At the same time the sides are pressed toward and interlocked with each other the head of the box becomes firmly seated in its groove. By providing the jaws with bearing bars h, the tenons at the corners may overlap or extend beyond the sides of the box and be subsequently finished off. The plate or support C being 40 of a size to fit within the completed box, prevents the sides from being moved inward toward each other too far; and by having a series of these plates C, one may be readily replaced by another and will act as a gage 45 to determine the size of the box. Of course,

when different sized boxes are to be made, 50 the posts or supports G and the fixed jaws will be adjustable upon the frame A as required.

Having thus described my invention, what I claim is—

1. The herein described box machine comprising the following elements in combination, to wit: the frame or bed A, the fixed jaws D D' secured thereto; the movable jaws E E' mounted to slide upon the bed and provided each with a roller m; the fixed posts G G; the levers F pivoted to the posts and provided with cam-slots l to receive the rollers m; and a stationary plate C to fit within and beneath the sides of the box and thereby support the bottom and sides. 65

2. In a box machine, the combination with the bed or frame A; of the jaws D D' mounted thereon; means for securing said jaws rigidly in different adjusted positions upon the bed; 70 the movable jaws E E' and posts G G also mounted upon the bed; means for securing the posts rigidly in their different adjusted positions; independent operating levers for the movable jaws mounted upon the posts; 75 and a fixed bottom-supporting plate also mounted in the bed.

3. In a box machine, the combination with the bed or frame; of two fixed jaws; two movable jaws and their actuating devices; 80 and a fixed plate to fit within and beneath the sides of the box and thereby support the bottom of the box and also the sides thereof.

4. In a box machine, the combination with a bed or frame; of jaws mounted thereon; and 85 a plate or support C, provided with a central portion b, and with lateral flanges c below the plane of the top of said central portion, whereby the bottom of the box will be held above the lower edges of the sides by the central portion of the plate. 90

In witness whereof I hereunto set my hand in the presence of two witnesses.

ROBERT SCHLEICHER.
